UNITED STATES PATENT OFFICE.

JOSEPH FR. TOPINKA AND FRANK B. JEDLICKA, OF CLEVELAND, OHIO.

PORTABLE ELECTRICALLY-HEATED STEAMING IRON.

Application filed April 18, 1927. Serial No. 184,594.

This invention relates to electrically heated portable steaming irons, which may also be converted into electrically heated portable steaming flat irons.

5 An object of the invention is to make a small, portable, self-contained steaming iron, which will quickly generate sufficient dry steam for use in steaming and pressing clothes, wash goods, furs, etc., and particularly for use with heavier garments, parts of which cannot be conveniently steamed and pressed by other means.

10 A further object is to provide an iron which may be used for dry steaming and pressing, or as a flat iron.

15 A further object is to provide a detachable flat iron element.

A further object is to provide a small portable steaming iron which will hold sufficient water to supply steam for a reasonable quantity of work, and that is self-contained, and need not be connected to a large steam supply boiler, etc.

20 Other objects will appear upon reading the specification.

In the accompanying drawings:

Figure 1 is a side view in elevation of the combined steaming and flat iron;

25 Figure 2 is a partial side view, in elevation, of the combined steaming iron and guard;

30 Figure 3 is a view, in perspective, of a detachable guard, shown attached in Figure 2;

35 Figure 4 is a vertical longitudinal section of the steaming iron, with the guard attached;

40 Figure 5 is an end view, in elevation, of the steaming iron, with the shell of the electric plug holder removed;

45 Figure 6 is a central transverse section on the line 6—6 of Figure 4, without the guard;

Figure 7 is a front end view, in elevation, of the steaming iron and guard;

50 Figure 8 is a top plan view of the detachable flat iron;

Figure 9 is a vertical longitudinal section on the line 9—9 of Figure 8;

55 Figure 10 is a rear end view, in elevation, of the detachable iron shown in Figure 9, and showing the cylinder casing of the steaming iron in dotted outline;

Figure 11 is a view in perspective of the electric heating unit for the steaming iron;

60 Figure 12 is a view, in perspective, on a reduced scale, of the water reservoir for the steaming iron;

Figure 13 is a view in perspective, of a concentric chambered casing to receive the 60 electric heating unit for the steaming iron;

Figure 14 is a broken view on a reduced scale, in perspective, showing one end of the chambered casing illustrated in Figure 13;

65 Figure 15 is a view, on a reduced scale, in perspective, of the conduit and sleeve which connects with the water reservoir shown in Figure 12; and

70 Figure 16 is a vertical longitudinal sectional view on a reduced scale, of the chambered casing shown in Figure 13.

The combined steaming iron and flat iron shown in Figure 1, has a cylindrical shell or casing 1, a handle 2, in which is a toggle 75 switch 3, a casing 4 to receive an electric attachment plug 5, a supply conduit 6 to admit water to the water reservoir, 10, see Figure 12, and a flat iron 7. In Figure 2 is shown the cylinder 1 with a guard 8 replacing the 80 electric flat iron; the guard is shown in Figure 3.

In Figure 4, the water conduit 6 is open at the end 9, to receive a hose to conduct water from a faucet, etc., to the reservoir 10, 85 the latter shown on a reduced scale in Figure 12, the reservoir having a suitable inlet 11, fitting in the extension tube 12 of casing 1, Figure 15, the opening to the inlet 11 being closed by the screw threaded plug 13, Figure 4, the conduit 6 being secured to the tube 12 and registering with an opening 14 in the inlet 11. The reservoir 10 is provided with a safety valve 15, to allow any excess steam pressure to escape. As shown in 90 Figure 12, the water in the reservoir 10 flows through pipes 16 into the outlet pipe 17, the latter provided with numerous holes 18, Figure 4, through which the water passes to the distributing or filtering envelope 19, 100 which in use becomes saturated with water to be converted into steam and serve as a steam-emission surface, and which may be made of asbestos or similar heat resisting porous material, and which retards or prevents the passage of water when cold, but is porous when heated. The ends of the pipe 17 are closed, as for example, by screw plugs 20, 20. When not in use, the plug 13, Figure 4, may be removed and the excess water 110 poured out.

The concentric chambered casing 21,

shown in Figures 13, 14 and 16, has an inner casing 22, and an outer casing 23, the inner casing 22 is closed at one end by the perforated disc 24, but open at the other end, at 5 25, shown in Figures 4 and 14; the outer casing 23 being closed at the end 26, Figure 14, and open at 27, Figures 13 and 16; the end of the outer cylinder of casing 23 is joined to the disc 28, Figures 13 and 16. 10 The pipe 17 with its asbestos covering 19, Figure 12, is inserted through the opening 25 into the inner casing 22, Figure 4, and after assembly, is secured to the disc 24 by the screws 20, Figure 4. A lava or other refractory insulating plug 30, Figure 4, is secured to or is integral with a tube 31, of alundum, or similar material, upon which is wound a heating coil 32, and then embedded in alundum cement 33, a partial view 15 of which, in perspective, is shown in Figure 11, the ends of the heating wire including the circuit 34 and toggle switch 3 in handle 2, are connected to the contact terminals 35, Figures 4 and 5, in the casing 4, and with 20 which the plug 5 makes contact. During use of the steaming iron, the guard 8, Figures 2, 3 and 4, may be applied if desired, to provide a smooth working surface, the guard having an opening 38, Figure 3, to 25 allow the steam to pass to the clothes. The guard 8 is attached to the body of the steamer casing 1 by the spring clips 39, which engage lugs 40, Figure 6.

A flat iron element, 41, Figures 8, 9 and 35 10, provided with spring clips 42, electric heating element 43, and contact terminals 44, which latter make contact with the lower sections 45 of the terminals 35, may be attached to the casing 1 upon the removal of 40 the guard 8. The flat iron is provided with a longitudinal groove 46, Figure 8, and a multiplicity of vents or holes 47, Figures 8 and 10, which latter may be flared outwardly if desired, to permit steam to pass 45 through and come in contact with the cloth when both steaming and pressing are being done at the same time. The electrically heated body of the iron serves to still further heat the steam passing through ducts or 50 passages 47. If it is not desired to use the steamer, the switch 3 is opened, the current then passing to the flat iron only. A suitable switch and connections 60 and 61 may also be provided to separately control the 55 current to the flat iron. The lower part of the casing 1 is provided with a tubular valve 50, Figure 4, consisting of a valve casing 51, and valve plug 52, the upper side of the casing is perforated with openings 53, which 60 register with openings 54 in the plug 52, the lower side of the casing 51 having a slot 55 registering with the lower holes 54 in plug 52; the openings 53, holes 54, and the slot 55, constitute ducts for the passage of 65 the steam; a handle 56 serves to adjust or

close the valve as may be desired. The flat iron 41 may be permanently attached to the cylinder 1, if desired, instead of being detachable by the springs 42.

To use the steaming iron, the reservoir 10 70 is filled with water through conduit 6, and the electric plug 5 is then connected, as shown in Figure 1, which supplies electric current to the heater 32; when the heating unit is sufficiently hot, the filtering envelope permits steam to pass, the steam entering the space surrounding the envelope 19, and passing through the opening 25 into the large space, then through the valve 50 and guard 8 to the cloth being steamed. If 80 the flat iron 41 is attached, the steam will pass through the openings 47 to the material being pressed.

We claim:

1. In a portable steaming iron having a 85 perforated working face, a reservoir to hold and supply water, a perforated outlet pipe to conduct water connected therewith, a porous filtering envelope covering said outlet pipe to receive and hold water therefrom, 90 and means surrounding said filtering envelope to heat the same and convert water into steam, and ducts being provided to discharge said steam through the working face of the 95 steaming iron.

2. In a portable steaming iron having a 100 perforated working face, a reservoir to hold and supply water, a perforated outlet pipe to conduct water connected therewith, a porous filtering envelope covering said outlet 105 pipe to receive and hold water therefrom and constructed to expose a distributed volume of said water to heat an electric heater surrounding said filtering envelope to heat the same and convert the water in said envelope into steam, means to protect said electric heater from steam, and a controlled outlet duct for the steam through the perforated working face.

3. In a portable steaming iron, a reservoir 110 to hold and supply water a perforated outlet pipe to conduct water connected therewith, means to convert the water issuing from the outlet pipe into steam, lugs on said iron, a perforated detachable smoothing element, 115 clamps on said element to detachably engage said lugs, and an outlet duct to conduct the steam through the outer surface of said element.

4. In a portable steaming iron, a reservoir 120 to hold and supply water, a perforated outlet pipe to conduct water connected therewith, an electric heater adjacent the reservoir and surrounding said outlet pipe to convert the water issuing therefrom into steam and to heat said reservoir, a smoothing element, clamps to hold said smoothing element on said iron, there being a steam discharge means through said element, and a duct to deliver the steam thereto. 130

5. In a portable steaming iron, a reservoir to hold and supply water, a perforated outlet pipe to conduct water connected therewith, a removable electric heater adjacent to said outlet pipe to convert the water issuing therefrom into steam, lugs on the casing of said steaming iron, electric circuits and contacts to conduct electricity to said electric heater, an electrically heated detachable flat iron base, electric connectors on said base to connect with said contacts, clamps on said base to engage said lugs, and an outlet duct to conduct the steam to the outer surface of said base.
- In testimony whereof we hereby affix our signatures.

JOSEPH FR. TOPINKA.
FRANK B. JEDLICKA.
